(57) **CLAIM**

The ornamental design for a zipper, as shown and described.

DESCRIPTION

FIG. 1 is a front perspective view of a zipper showing my new design.

FIG. 2 is a front view of the zipper of FIG. 1.

FIG. 3 is a rear view of the zipper of FIG. 1.

FIG. 4 is a left view of the zipper of FIG. 1.

FIG. 5 is a right view of the zipper of FIG. 1.

FIG. 6 is an enlarged top view of the zipper of FIG. 1; and, FIG. 7 is an enlarged bottom view of the zipper of FIG. 1. The broken lines in the drawings represent portions of the zipper and form no part of the claimed design.

The zipper is shown with a symbolic break in its length. The appearance of any portion of the zipper between the break lines forms no part of the claimed design.

1 Claim, 7 Drawing Sheets
